Primary Examiner — Susan Bennett Hattan*Assistant Examiner* — Jennifer Wright(74) *Attorney, Agent, or Firm* — Brooks Acordia IP Law, PC(57) **CLAIM**

The ornamental design for a boot, as shown and described.

DESCRIPTION

FIG. 1 is a perspective elevation view of a boot showing our new design;

FIG. 2 is a front plan view of FIG. 1;

FIG. 3 is a back plan view of FIG. 1;

FIG. 4 is a right plan view of FIG. 1;

FIG. 5 is a left plan view of FIG. 1;

FIG. 6 is a top plan view of FIG. 1; and,

FIG. 7 is a bottom plan view of FIG. 1.

The broken lines on the exterior of the boot in FIGS. 1-7 depict stitching that form part of the claimed design.
